ABSTRACT OF THE DISCLOSURE

A photo-engraving apparatus capable of utilizing printing cylinders of varying length and diameter wherein pressure rollers are carried by arms pivoted to the frame of the apparatus and the lamp housing of the apparatus is similarly pivoted to the frame to facilitate substitution of printing cylinders. The cylinder support bearings are made to be readily movable in a direction parallel to the cylindrical axis to enhance handling of varying cylinder lengths. The pressure rollers are mounted resiliently on the support arms to increase the effectiveness of the operation of the apparatus.

The present invention relates to an apparatus for copying, by light exposure, designs and lettering from a photographic film on a sensitized printing cylinder, the apparatus also being suitable for use in photo-engraving techniques. More particularly, the invention relates to an apparatus for the processing of medium and small sized printing cylinders which may have differing body and shaft diameters and to the facilitated interchangeability of such printing cylinders.

It is an object of the present invention to make available a simplified apparatus for producing reproducible images which can be manufactured and sold at a lower cost and with a reduction in required materials without sacrificing efficiency when compared to other more complicated devices. In use, the apparatus of the invention will promote efficiency in photo-engraving processes by reducing the time and effort required to remove and reinstall the printing cylinder of the apparatus. The apparatus of the invention, therefore, is designed to facilitate the installation and use of printing cylinders having face lengths of about one to thirty inches and a variety of supporting shaft diameters.

The use of the apparatus will promote efficiency and will save time and labor in the engraving process by its easy operation and its adaptability to different cylinder diameters and shaft sizes and further, by its capability to serve besides copying, for other necessary functions, such as developing the exposed cylinder, cleaning and drying it while rotating and possibly even etching and later finishing the cylinder as needed.

In the apparatus of the invention, provision is made for the utilizing of pivotally mounted elongated pressure rollers which are designed to bear against the printing cylinder as it is rotated on its bearings. These pressure rollers are carried by arms which are pivoted to opposite ends of the frame of the apparatus and which can be positioned and maintained in preselected positions with respect to the printing cylinder. Both the pressure roller support arms and the rollers themselves can be pivoted out of the way of the printing cylinder to facilitate the removal of the cylinder and replacement of another of either the same or different diameter and/or length. The pressure rollers can then be rotated back into contact with the printing cylinder being adjustable to conform to the diameter of the new cylinder.

The pressure rollers in the apparatus of the invention while capable of accommodating a variety of diameters

and lengths of printing cylinders in a copying or photo-engraving apparatus, act to maintain a uniform predetermined pressure on the cylinder on which they engage.

In addition to the pivotal mounting of the dual pressure rollers to the frame of the photo-engraving apparatus, the lamp housing structure is also pivoted to the frame of the apparatus. The pivotal mounting of the lamp housing of the unit acts in conjunction with the pivoted rollers to facilitate and expedite the interchange of the printing cylinders and the servicing of the components of the lamp housing. When it is desired to replace or substitute printing cylinders, it is a fairly simple matter to pivot the lamp housing and its contents a predetermined distance in order to clear the area of the printing cylinder so that it may be replaced.

The apparatus of the invention therefore provides a construction which will permit the controlled exertion of pressure on printing cylinders of widely varying diameters and lengths, and will facilitate the replacement of the cylinders in a manner such that the versatility of a single photo-engraving apparatus can be greatly enhanced.

Various objects and advantages of the invention will become more fully apparent from the following description of the drawings illustrating presently preferred embodiments thereof and wherein:

FIG. 1 is a partial end elevational view of an apparatus of the invention illustrating, in particular, the pivotally mounted lamp housing and pressure rollers;

FIG. 2 is a partial side elevation of the photo-engraving apparatus of the invention; and

FIG. 3 is a fragmentary end elevational view illustrating a means for adjusting a pressure roller supporting arm.

The basic elements of the copying or photo-engraving apparatus of the invention are illustrated in FIGURE 1. An end stand, generally designated 1, which is a frame element of the unit, is suitably supported by a base (not shown) and, as is shown in FIG. 2, a second end stand, generally designated 2, which is similar to end stand 1 in its material aspects, is positioned in spaced relationship with respect to stand 1. Stands 1 and 2, as seen in FIGS. 1 and 2, are interconnected and braced by a pair of reinforced side rails 3 and 4. Additional cross-bar bracing (not shown) can be employed in connection with the supporting base. These side rails are carefully aligned with each other in a manner such that the inner and upper rail surfaces are in parallel relationship and at the same vertical level on the opposed end stands.

The side rails 3 and 4 serve to support a pair of independently movable cylinder shaft support bearings which are generally designated 5 and 6 and best illustrated in FIG. 2. It can be seen in FIG. 1 that cylinder shaft support bearing 5 is movable longitudinally on the side rails of the apparatus on wheels 7 and 8 which are designated to freely roll upon these rails. Wheels 7 and 8 of support bearing 5 are rotatably mounted thereon between guide elements 9 and 10 and 11 and 12, respectively, which are secured to and depend vertically from support plates 13 and 14 carried by the support bearing 5. These plates are connected to cross-support 15 of the cylinder shaft support bearing 5. The cross-support 15, as is best viewed in FIG. 1, serves to interconnect the guide elements of wheels 7 and 8 and to act as a platform for a housing 16 which carries a pair of wheel bearings 17 and 18. The wheel bearings 17 and 18 are positioned in housing 16 in spaced relationship with their axes parallel to that of the rails and are freely rotatable in the housing. A portion of each of the spaced wheel bearings protrudes above the housing to rotatably receive and support one end of the support shaft 19 of a printing cylinder 20.

The structural features of cylinder shaft support bearing 6 is similar to that of bearing 5 and, where necessary for

descriptive purposes, the applicable reference numerals of bearing 5 will be applied to the identical parts of bearing 6. As can be seen in FIG. 2, both bearings 5 and 6 can be moved along the rails 3 and 4 of the apparatus on wheels 7 and 8 to accommodate a virtually infinite number of printing cylinder lengths on wheel bearings 17 and 18. The overall diameter of the printing cylinder 20 which is supported between movable bearings 5 and 6, as can be seen in FIG. 2, can also be widely varied.

Referring to FIG. 1, it can be seen that bearing housing 16 is fabricated in the form of a generally U-shaped yoke with the legs of the yoke depending from the base thereof. A threaded shaft 21 is positioned with an end in engagement with the base of the yoke and with its other end projecting through cross-support 15 of the cylinder shaft support bearing. An enlarged supporting nut 22 is threaded onto shaft 21 and is adapted to rest upon cross-support 15 in predetermined position with the base of the yoke of bearing housing 16 resting thereupon. By securing the end of shaft 21 projecting from cross-support 15 and by rotating the supporting nut 22 in one direction or the other, the vertical position of wheel bearings 17 and 18 can simply be adjusted to accommodate a wide range of diameters of printing cylinder supporting shafts 19. This adjustment is important in making it possible to use a drive system which can be maintained at a fixed level while the vertical position of wheel bearings 17 and 18 can be adjusted through shaft 21 and nut 22 to align various cylinder shaft diameters with the drive system. Both cylinder support bearings 5 and 6 use similar adjustment means.

The end stand 1, as shown in FIG. 1, consists of a pair of spaced end posts 25 and 26 connected by a cross-member 27 and disposed in raised relation thereto with end post 25 in slightly elevated relation with respect to post 26, and end stand 2 is similarly constructed. A pair of pillow blocks 28 are mounted upon a support plate 29 and both are rigidly secured to cross-member 27 of end stand 1. These pillow blocks are provided with an aperture 30 through which drive shaft 31 projects. The drive shaft, which is driven from a source not shown, is coupled to cylinder support shaft 19 by a sleeve coupling 32 secured to the respective shaft ends and serves to rotate the cylinder 20 at predetermined speeds.

As shown in FIG. 1, a pair of roller arms 35 and 36 are pivotally mounted to the raised portions of end posts 25 and 26, respectively, of end stand 1. Each of the roller arms 35 and 36 are keyed at 37 and 38, respectively, to shafts 39 and 40, respectively. Shaft 40 extends in parallel relationship to the longitudinal axis of cylinder 20 from end post 26 to the opposite end post 41 of end stand 2 and is journaled in bronze bushings therein for rotation as is shown in FIG. 2 and projects a short distance through the opposed end posts. A third roller arm 42, shown in FIG. 2, is keyed to shaft 40 adjacent to end post 41 in a manner such that both roller arms 36 and 42 are maintained at the same angle of elevation at all times on shaft 40. While not shown in FIG. 2 for purposes of clarity, shaft 39 also projects in parallel axial relationship with cylinder 20 from end post 25 to a corresponding end post on end stand 2 where it is journaled. A fourth roller arm (not shown) is keyed to shaft 39 in a manner similar to arm 42 to maintain it at the same angle of elevation as arm 35 at all times on the shaft.

Lever arms 45 and 46 are keyed at 47 and 48, respectively, to shafts 39 and 40 on the sides of end posts 25 and 26 of stand 1 opposite that of roller arms 35 and 36. The lever arms are designed in a manner such that upon manually depressing either or both of them, the corresponding roller arms are thereby proportionately elevated.

As is shown in FIG. 3, the end of shaft 40 which projects from the end post 26 is provided with ratchet teeth 50 extending from the periphery thereof and into engagement with a pawl 51 pivoted to end post 26 and biased into normal operative position by a leaf spring 52. The

pawl and ratchet arrangement illustrated serves to permit the application of additional downward pressure to the rollers and against the printing cylinder and to maintain the roller arms 36 and 42 in a predetermined elevated position with respect to the cylinder 20 when the pressure rollers are not in use. The pawl 51 may be manually biased against the leaf spring 52 to release the ratchet and thereby lever actuated shaft 40 to move the roller arms in an opposite direction. As can be seen in FIG. 1, shaft 39 and end post 35 are similarly equipped with a pawl and ratchet arrangement to produce the controlled movement of the roller arms connected thereto.

FIG. 1 most clearly illustrates the construction of the roller supporting ends of arms 35 and 36 which are identical in all material respects to the end construction of the roller arms pivoted adjacent to end stand 2. The roller arms are formed with generally U-shaped slots 53 which open upwardly from the end of each arm. A bushing 54 contained by a generally spool-shaped rim 55 having the top surface 56 thereof sheared-off is inserted into each of the U-shaped slots. When in proper operative position, the flat top surface 56 of each rim 55 faces upwardly from the U-shaped slot 53, and the bushing centers of each of the arm pairs are aligned in co-axial relationship. A squared end spring 57 is inserted into each of the U-shaped slots and rests on the top flat surface 56 of rim 55. A spring cover 58 is secured to each of the arms over the U-shaped slots 53 by bolts 59. Cover 58 is provided with a centrally located projection 60 which is inserted into the inner diameter of the squared end spring 57 to properly align the spring with respect to the cover, rim and slot and thereby produces effective floating bearings for the pressure cylinders.

Referring to FIGS. 1 and 2, pressure rollers 65 and 66, which have an outer resilient covering such as rubber, are rotatably mounted by shafts 67 and 68, respectively, in the co-axial bushings 54 carried by arms 35 and 36, respectively, and the arms interconnected and aligned therewith by shafts 39 and 40, respectively. The pressure rollers 65 and 66 are thereby resiliently mounted in floating bearings on the arms and can resiliently respond through the spring biased bushings and rims to the operation of the cylinder 20 as it rotates under the pressure contact of rollers 65 and 66.

The rollers 65 and 66 serve to guide a film being processed with some pressure along the surface of the rotating printing cylinder 20 during the copying phase of the process. In addition to the guiding function, the rollers also exercise a tensioning action on the film and produce a close contact between the film and the cylinder surface. To augment the tensioning of the film on cylinder 20, a simple brake consisting of an arm 61 pivoted to roller support arm 42 at 62 can be rotated into engagement with shaft 68 of the roller 66 to stop or to selectively reduce the amount of rotation of roller 66 as is required in tensioning film being processed. By slowing the rotation of roller 66 in relation to the surface speed of the film on printing cylinder 20, front roller 66 can produce a squeegeeing action to any fluid used in connection with the copying process.

To reduce the torque exerted on the outer ends of the roller arms by adjustments made of lever arms 45 and 46, a pair of connecting rods 69 and 70, positioned in parallel axial relationship to cylinder 20, are secured to the arms controlled by shaft 39 and another pair of axially parallel connecting rods 71 and 72 are secured to arms 36 and 42 as shown in FIG. 1. These connecting rods act to impart rigidity to the respective shaft and arm structures during operation of the photo-engraving apparatus and to maintain the pressure rollers in constant parallel alignment with the longitudinal axis of cylinder 20. The rods also serve to prevent the deflection of either of the arms or associated pairs from their original alignment after extensive raising and lowering of the pressure rollers. For purposes of clarity, connecting rods 71 and 72 which

extend horizontally between and are connected to arms 36 and 42 have been omitted from FIG. 2.

To further facilitate the removal and replacement of cylinder 20 of the photo-engraving apparatus, the lamp housing and its contents, which ordinarily include a high intensity mercury vapor lamp and are generally designated 75, is supported by an arm 76 keyed at 77 to a rotatable shaft 78, positioned axially with respect to cylinder 20, which is journaled in end post 25 of end stand 1 and is generally vertically spaced above roller arm shaft 39. This arm 76, as in the case with respect to the roller arms 35 and 36, has a corresponding arm keyed to shaft 78 at a point adjacent end stand 2 of the apparatus. These arms are positioned at the same angle of elevation on the shaft 78 and are secured at opposite ends of lamp housing 75. A pair of horizontally extending connecting rods 79 and 80, which are axially aligned with shaft 78 and cylinder 20, extend between and are connected to the lamp housing support arms. They act in the same manner as those employed in connection with the roller arms.

The lamp housing has an adjustable slotted opening 83 through which the light beam is directed on top of the rotating cylinder. The mercury lamp is suspended within the housing and it is also possible to raise or lower the lamp somewhat within the housing if needed. The lamp housing itself rests on two cross rods 84 and 85 which in turn are connected with the supporting arms. A slot in front of the top of the supporting arms permits by means of a set screw and a pivotal action of the housing to direct and center the light beam still better if needed. The lamp housing is also generally provided with an exhaust system to prevent overheating.

A ratchet and pawl arrangement, similar in all material respects to that illustrated in FIG. 3 in connection with the adjustment of arm 36, is provided on the end of shaft 78 projecting from end post 25 and on end post 25. A lever arm 81 is keyed at 82 to the projecting end of the shaft 78 and acts to produce the manual adjustment of the lamp housing with respect to cylinder 20.

Again, for purposes of clarity, the lamp housing and supporting structure has been omitted from FIG. 2 since the construction is believed to be fully understandable from the illustration of FIG. 1 and the mounting of roller 66 in FIG. 2.

In operation, cylinder support bearings 5 and 6 are moved on rails 3 and 4 until they have been spaced apart a distance determined by the length of the cylinder 20 and the supporting shaft 19 projecting therefrom. Lever arm 46 is depressed to elevate the pressure roller 66 supported by arms 36 and 42 and rigidly interconnected by rotating shaft 40 and connecting rods 71 and 72. The arms and rollers supported thereby are moved out of the area cylinder support bearings 5 and 6 and into an inclined position with respect to posts 26 and 41. A similar operation is performed with respect to lever 45 to move roller 65 and its supporting structure away from the area of the cylinder support bearings until the arms thereof rest against lamp housing pivot shaft 68. Next, lamp housing 75 and its contents are elevated and rotated out of the cylinder support bearings area by actuation of the manually operable lever arm 81 and may be dropped until it rests in an inclined position against the frame. In each of the above cases, the position of the pressure rollers and lamp housing when moved out of the area of the cylinder support bearings is maintained by a ratchet control arrangement of the type illustrated in FIG. 3 or by resting upon some portion of the frame.

The supporting shaft ends 19 of the cylinder 20 are placed on the wheel bearings 17 and 18 of cylinder support bearing 5 and the similar structure of cylinder support bearing 6. After the cylinder has been properly positioned, the left end of shaft 19, as shown in FIG. 2, is coupled to drive shaft 31 which projects through pillow block 28 supported on cross-member 27 of end stand 1. The coupling 32 acts to rigidly lock the drive shaft 31

to the cylinder support shaft 19 whereby the cylinder may be rotated by a suitable motive force at a predetermined rate.

To place the cylinder 20 in its operative position, both pressure rollers and support arms are rotated by levers 45 and 46 until rollers 65 and 66 come into substantially complete pressure exerting engagement with portions of the periphery of cylinder 20, and lamp housing 75 is rotated by lever 81 into its normal operative position vertically above the longitudinal axis of the cylinder 20. Since pressure rollers 65 and 66 extend almost complete width of the span between end stands 1 and 2, the pressure exerted thereby can be used effectively on either elongated or short cylinders. Further, since the rollers are pivotally mounted, the cylinder diameters can vary over a wide range while maintaining effective pressure contact with the rollers. And, due to the simplicity of operation of the apparatus, the rollers can be elevated or adjusted at any time during the copying or photo-engraving operation.

As to the lamp housing 75, this can be more effectively maintained and repaired by rotation to a position which is more conveniently accessible.

Various modes of carrying out the invention are contemplated as being within the scope of the following claims particularly pointing out and distinctly claiming the subject matter which is regarded as the invention.

I claim:

1. An apparatus for producing a reproducible image on a cylinder comprising a frame, a lamp housing associated with the frame, means on the frame for rotatably supporting the cylinder on a predetermined axis, a roller support arm having first and second ends, the first end of the arm being pivotally connected to the frame in a fixed position on the frame substantially immovable with respect to the axis of the cylinder, the second end of the roller support arm being a substantially free end for selective disposition in preselected angular relationships with respect to the predetermined axis of the cylinder, co-operable means on the frame and on the roller support arm operatively linked together and disposed adjacent the pivotal connection of the arm to the frame and the first end of the arm for establishing a predetermined angular relationship between the second end of the arm and the periphery of the cylinder and for producing the selectively controlled arcuate movement of the support arm toward and away from the axis of the cylinder, and a pressure exerting roller assembly including a roller rotatably carried by the roller support arm adjacent the second end thereof.

2. An apparatus according to claim 1, wherein resilient biasing means are connected to the roller support arm adjacent the second end thereof and disposed in resilient engagement with at least a portion of the roller assembly for producing the resilient and rotatable support of the pressure exerting roller on the roller support arm.

3. The apparatus of claim 1, including a second roller support arm pivoted to the frame of the apparatus, a second pressure exerting roller assembly rotatably supported on the second arm and being movable into and out of contact with the cylinder along the longitudinal axis thereof, the pivotally supported pressure rollers being disposed with their longitudinal axes in parallel relationship.

4. The apparatus of claim 3, wherein the means on the frame for rotatably supporting the cylinder on a predetermined axis comprise at least a pair of spaced bearing means locatable at opposite ends of the cylinder, at least one of said pair of bearing means being mounted upon rollers carried by track means connected to the frame and extending in parallel relationship with respect to the cylinder axis, the roller mounted bearing means being freely movable on the track means and in parallel relation with the axis of the cylinder to accommodate cylinders of varying axial lengths.

5. The apparatus of claim 1 wherein the lamp housing of the apparatus is pivotally connected to the frame there-

of to permit movement of the lamp housing into and out of its normally operative position with respect to the cylinder.

6. The apparatus of claim 1, wherein the pressure exerting roller assembly includes a first roller and supported by a first plurality of roller support arms pivoted to the frame in fixed positions on the frame and in spaced relationship and being simultaneously actuatable to adjust the position of the first roller with respect to the longitudinal axis of the cylinder, a second plurality of spaced roller support arms pivoted to the frame of the apparatus in fixed positions with respect thereto and being simultaneously actuatable for selective adjustment of their position with respect to the longitudinal axis of the cylinder, a second pressure exerting roller rotatably supported by the second plurality of support arms, the first and second plurality of support arms being pivotally connected to the frame of the apparatus adjacent the first ends thereof and on opposite sides of the cylinder, the longitudinal axes of the first and second rollers being positioned in parallel alignment each with the other and both with the longitudinal axis of the cylinder, the pivotally mounted support arms being adjustable in a manner permitting the exertion of pressure by the rollers carried adjacent the second ends thereof on a wide range of cylinder diameters and being pivotable to an angle facilitating the removal and replacement of cylinders without substantial disruption of the apparatus

7. The apparatus of claim 6, wherein the lamp housing of the image producing apparatus is pivotally connected to the frame thereof, the lamp housing being positioned in normally operative axially aligned relationship with the cylinder at one extreme of its pivotal movement and being pivotable out of interfering relationship with respect to the cylinder, the pivotally mounted lamp housing and pressure

rollers acting co-operably to facilitate removal and replacement of cylinders.

8. The apparatus of claim 6, wherein the first plurality of roller support arms are interconnected by a shaft as are the second plurality of roller support arms and ratchet means are co-operably connected to the frame of the apparatus and to the shafts to permit the predetermined simultaneous angular adjustment of the rollers with respect to the printing cylinder.

9. The apparatus of claim 7, wherein the lamp housing is pivotally mounted on the frame of the apparatus by a plurality of spaced lamp support arms pivoted thereto, the spaced support arms being interconnected by a shaft, and angular adjustment means co-operably connected to the frame of the apparatus and to the shaft to permit the predetermined and simultaneous angular adjustment of the lamp arms and the lamp housing carried thereby with respect to the printing cylinder.

10. The apparatus of claim 1 wherein a friction braking lever is pivotally connected to the frame and having a portion thereof disposed adjacent the pressure exerting roller assembly for selectively altering the rotation of the rotatable pressure roller by the frictional engagement of the lever with a portion of the roller assembly.
